UNITED STATES PATENT OFFICE

THEODORE A. FEDERWITZ AND WALTER T. BAILEY, OF PHILADELPHIA, PENNSYLVANIA, ASSIGNORS TO STOKES AND SMITH COMPANY, OF PHILADELPHIA, PENNSYLVANIA, A CORPORATION OF PENNSYLVANIA

CONVEYING SYSTEM

Application filed November 21, 1925. Serial No. 70,462.

Our invention relates to the art of feeding wrappers, sheets, labels, or equivalent, hereinafter termed "sheets," to a machine or unit, as a wrapping machine, a box-wrapping or 5 covering machine, a package-wrapping machine, a can-wrapping machine, or equivalent, hereinafter termed a "wrapping unit" or "wrapping machine," which applies the sheet to any desired box structure.

10 In accordance with our invention, sheets, as aforesaid, are coated, either partially or entirely, with adhesive by suitable mechanism, as an adhesive applying unit and are fed, preferably directly from the glue roll 15 of said unit to sheet gripping mechanism actuated in timed relation with said unit.

Further in accordance with our invention, a system of moving tubes or rods pneumatically retaining individual sheets in engagement therewith functions to deliver said sheets in timed relation to a wrapping unit, as aforesaid, and more particularly, said system comprises a reciprocatory tube or tubes 20 pneumatically retaining an individual sheet 25 in engagement therewith while moving in one direction to transport the sheet to a station, where it is pneumatically retained after release from said tube or tubes.

Further in accordance with our invention, 30 individual sheets are transported from suitable mechanism, as an adhesive-applying unit, toward a wrapping machine, as aforesaid, by conveying mechanism comprising structure for mechanically gripping the retaining individual sheets during transportation through one region and by other conveying mechanism comprising structure for pneumatically retaining individual sheets during transportation through another region, 35 and more particularly, said conveying mechanism first mentioned is operated to effect a higher velocity of sheet movement than is effected by said conveying mechanism second mentioned.

40 Further in accordance with our invention, a system comprising a tube or tubes pneumatically retaining a sheet while effecting delivery to a station comprising pneumatic sheet-retaining structure is controlled by a 45 suitable master valve, to the end that the sheet

may be substantially simultaneously released from said tube or tubes and pneumatically secured to said retaining structure.

Our invention resides in the system, apparatus and features of structure hereinafter 55 described and claimed.

20 Referring to the drawings, there is shown an adhesive-applying unit G and a wrapping machine W, or equivalent, as aforesaid, said wrapping machine comprising the form block structure w. Unit G and machine W are co-operatively related by mechanism which synchronizes the operations or movements of the unit G with the operations or movements 25 of the machine W and by a conveying or transferring unit C delivers to the wrapping machine W boxes, or equivalent, as aforesaid, and sheets, or equivalent, as aforesaid, 30 the latter gummed or glued and delivered by the unit G to the transferring unit C.

The adhesive-applying unit G may be of any suitable type capable of applying adhesive to sheets of box-wrapping paper, or 35 other suitable material, and delivering the gummed sheets in succession at uniform intervals. In the example illustrated, the unit G is of the same general type disclosed in Nitsch and Federwitz Letters Patent No. 40 1,472,614, granted October 30, 1923.

The wrapping machine W may be of any suitable character, and in the example illustrated is broadly of the type disclosed in prior Letters Patent to Smith No. 691,329, 45 and more specifically of the type disclosed in prior Letters Patent to Nitsch and Federwitz No. 1,540,900, and still more specifically of the character disclosed in our prior Letters Patent Nos. 1,541,036 and 1,541,255.

50 The conveying unit C, however, is of novel construction, and is preferably of such form as to constitute a unit which may be added as an attachment to or a bridge for another set of machines or mechanisms, or more particularly to a wrapping machine W, or equivalent, and an adhesive-applying unit G, or equivalent.

The adhesive-applying unit G is driven at 60 suitable speed by any suitable source of power and operates to move single sheets in succession from the stack d of unglued sheets through the rotary feed roll mechanism designated generally at b and into engagement with the gluing roll c, where there is applied, on one side thereof, any suitable ad-

hesive, as glue. The sheets after being stripped and deflected from the glue roll c are engaged and transported by conveying mechanism associated with the adhesive-applying unit G, as hereinafter described. 70

Sheet transporting mechanism of the conveyer unit

The unit C comprises a base 1 supporting a casing 2, from which rise the parallel spaced 75 side frames 3 and 3a.

A shaft 4, journaled in the frame of the wrapping unit W and the casing 2 carries a pulley P driven by any suitable source of power and a worm gear 5 meshing with and 80 rotating a worm wheel 6, preferably formed integrally with a barrel or drum cam 7 rotatably mounted in the casing 2. A cam track 8, formed on the outer surface of cam 7, receives a roller 9 rotatably mounted on a stud 85 10 carried by one arm of a bell crank lever 11 pivoted to the casing 2. The other arm of lever 11 terminates in a gear quadrant 12, meshing with a pinion 13 keyed to a shaft 14 mounted in bearings in the side frames 3 90 and 3a.

Exteriorly of side frame 3a, a gear 14m, keyed to shaft 14 meshes with a gear 14n keyed to a shaft 15 mounted in bearings on side frame 3a. A gear 16, keyed to shaft 95 15, meshes with a gear 17 freely rotatable on a shaft 18 mounted in bearings in the side frames 3 and 3a.

Shaft 18 may be manually rotated independently of gear 17 to effect adjustment of 100 certain rack structure, hereinafter described. When so adjusted, gear 17 may be secured to shaft 18 in any suitable manner, preferably, however, by a flanged collar 19 formed integrally with said gear, with which co-acts a 105 collar 20 secured to shaft 18. A clamping bolt or screw 21 passes through a circumferential slot 22 in collar 20, and when threaded into collar 19, Figs. 10 and 13, binds the two collars together, to the end that rotation 110 of shaft 18 is effected in response to rotation of gear 16. If desired, the face of collar 19 removed from gear 17 may be provided with a suitable scale, as indicated in Fig. 13, and collar 20 may be formed with a pointer 115 23 movable over the scale.

A pair of conveyer frames 24 and 24a, each adjustable in a lateral sense are supported by rods R and R1 extending transversely of and carried by side frames 3 and 3a. Any suitable mechanism may be utilized to effect equal and simultaneous adjustments of each of said conveyer frames either toward or from the longitudinal axis of the conveyer unit C whereby sheets of various lengths may be 120 conveyed. If desired, this mechanism may take the form of that disclosed in our prior application Serial No. 40,769, filed July 1, 1925. Brackets 25 and 25a, carried respectively by conveyer frames 24 and 24a, are 125 130

arranged to rotatably support the sleeves 26 and 26a, splined to shaft 18, Fig. 10. Gear wheels 27 and 27a, suitably secured, respectively, to sleeves 26 and 26a, mesh with racks 28 and 28a suitably secured respectively to sleeves 26 and 26a. Carried by each rack are the spaced arms 29, Figs. 5 and 10, supporting the reciprocatory sheet-transporting suction tubes 30 and 30a in substantially parallel relation with racks 28 and 28a.

10 Suction tubes 30 and 30a may be placed in communication with a master or control valve, hereinafter described, in any suitable manner. As one manner of so doing, a chamber 31, Figs. 6 and 15, provided with a flexible tube 32 leading to the control valve is connected to suction tube 30 by one or more passages 33. It is to be understood that suction tube 30a is likewise placed in communication with the control valve in a manner similar to that described above. To this end, a flexible tube 32a, leading to the chamber corresponding with chamber 31, is joined with tube 32, Fig. 7, and from the point of juncture, a tube 34 leads to the master or control valve V, hereinafter described.

Extending inwardly toward the center line of the machine are the arms 35 and 35a, carried, respectively, by the brackets 25 and 25a, Fig. 10, the extremities of said arms, respectively, adjustably supporting guide members 36 and 36a, in turn supporting the stationary sheet-retaining suction tubes 37 and 37a disposed substantially parallel with tubes 30 and 30a. Adjacent the wrapping machine W, Fig. 16, one end of tube 37a slidably mounted on a guide member 38a supported by a stud 39a extends through the conveyer frame 24a while adjacent the unit G, the end of tube 37 is shown as resting upon a guide member 40 slidably supported by a stud 41 extending through the conveyer frame 24, Figs. 1 and 4.

It is to be understood that the end of tube 37 adjacent the wrapping machine W is supported in a manner similar to that described with respect to tube 37a, and that the end of tube 37a adjacent the unit G is supported in a manner similar to that described with respect to tube 37.

The ends of stationary suction tubes 37 and 37a extend into the region occupied by the sheet-delivery mechanism of the adhesive-applying unit. Some distance from their immediate ends, said tubes are each provided with a plug 42, Fig. 4, whereby each tube is divided into two distinct chambers. A pipe or conduit 43 opens into a fitting 44 having a passage 45 in communication with the chamber in tube 37 nearest to the adhesive-applying unit. A similar pipe or conduit 43a opens into the corresponding chamber in tube 37a.

Another pipe or conduit 47 opens into the chamber in tube 37 nearest the wrapping machine W, and a second pipe or conduit 47a

opens into the corresponding chamber in tube 37a.

Referring to Fig. 6, suction tube 48 is shown as extending from the chamber 31, which is carried by the reciprocatory rack 28. Said tube passes through a bearing 49 comprised in conveyer frame 24, and extends toward and beyond the form block structure of the wrapping machine. A suction palm 50 is secured to an angular extension 51 of said suction tube substantially in alignment with the reciprocatory suction tube 30.

It is to be understood that a similar suction palm 50a, Fig. 7, substantially in alignment with reciprocatory suction tube 30a, is likewise connected to a suction tube 48a corresponding with tube 48.

Reciprocatory suction tubes 30 and 30a are provided at their ends and intermediate thereof with pairs of perforated suction heads 52 aligned transversely of the machine, the distance along each tube between neighboring suction heads being at least as great and preferably somewhat greater than the maximum width of sheet to be transported. Stationary suction tubes 37 and 37a are likewise provided at their ends and intermediate thereof with pairs of perforated suction heads 53, aligned transversely of the machine and spaced to correspond with the distance between suction heads 52. The suction palms 50 and 50a at the ends of tubes 48 and 48a are provided with one or more perforations or suction openings.

Oscillatory movement imparted to gear 100 quadrant 12 by cam 7 is eventually transmitted to shaft 18, and as the latter moves first in one direction and then in the other, racks 28 and 28a function to reciprocate the movable suction tubes 30 and 30a longitudinally of the machine.

The sheet-supporting belts

As individual sheets are transported from the adhesive-applying unit G toward the wrapping machine W, it is desirable that such sheets be supported by suitable belt structure movable with the sheets, but remaining at rest during the intervals the sheets are at rest. To this end, it is necessary to effect intermittent step-by-step movement of the belt structure.

Shaft 18, as stated above, intermittently rotates, first in one direction and then in the other, and may be utilized to effect intermittent step-by-step movement of the belt structure. Preferably, such movement is attained by utilizing clutch mechanism of a type well known in the art to effect intermittent rotation of a belt-advancing pulley 125 always in the same direction. To this end, and referring to Figs. 10, 11, and 12, a clutch spider 55a is suitably secured or formed integrally with sleeve 26a for rotative movement therewith. A pulley 56a, freely rotat-

able on sleeve 26a, is provided with a circumferential recess 57a receiving spider 55a, said spider 55a comprising a series of radially tapering pockets 58a receiving the cylindrical rollers 59a, each biased into engagement with the adjacent surfaces on pulley 56a and spider 55a by a shoe 60a engaged by a coil spring 61a.

It is to be understood that sleeve 26 is equipped with mechanism, including a belt pulley 56, which is a duplicate of that just described, and, accordingly, for the sake of brevity, the description will not be repeated.

Adjacent the wrapping machine W, the stud 39a carried by conveyer frame 24a forms a bearing for an idler roll 62a, Fig. 16, while adjacent the unit G, the stud 41a, also carried by conveyer frame 24a, forms a bearing for another idler roll 63a, Fig. 9. A side belt Ba passes over idler rolls 62a and 63a and beneath the drive pulley 56a.

A side belt B, corresponding with belt Ba, passes over an idler roll 63 mounted on stud 41 carried by side frame 24, adjacent the unit G, Fig. 9, and over an idler pulley, not shown, but corresponding with roll 62a adjacent the wrapping unit W. Side belt B also passes beneath drive pulley 56, Fig. 10, and is maintained in engagement therewith by idler rolls 64 and 65, suitably secured to the bracket 25, as by the stud 66, Fig. 2. It is to be understood that side belt Ba is maintained in engagement with its drive pulley 56a by a corresponding set of idler pulleys, not shown.

Referring to Fig. 2, intermittent clockwise movement is imparted to pulley 56 through the clutch mechanism described above, and as a result, the upper span of belt B intermittently advances toward the wrapping machine W coincidentally with movement of racks 28 and 28a in the same direction. During reverse movement of said racks, pulley 56 and belt B remain stationary. Obviously, pulley 56a and belt Ba are controlled in a similar manner.

Referring to Figs. 2, 5 and 10, a bar 67, extending between and secured to the side frames 3 and 3a, supports a pair of brackets 68 and 69, forming a bearing for a sleeve 70 splined to shaft 18. A drive pulley 71, freely rotatable on sleeve 70, may be controlled by suitable clutch mechanism, for example, as described above with respect to pulleys 56 and 56a, to lock the same to shaft 18 when it rotates in a clockwise direction, Fig. 2, and release the same when said shaft rotates in reverse direction. Adjacent the wrapping machine W, Figs. 6 and 16, a center belt B1 passes over an idler pulley 72 mounted on a shaft 73 mounted in a bracket 73m secured to the conveyer frames 24 and 24a, by supporting structure, not shown. Adjacent the adhesive-applying unit G, belt B1 passes over an idler pulley 74 mounted on a shaft 75 mounted in a manner similar to that described

above with respect to shaft 73. Belt B1 also passes beneath drive pulley 71, and is held in engagement therewith by idler rolls 71m and 71n journaled in brackets 68 and 69.

It is to be understood that belt B1 moves in synchronism with belts B and Ba, and in so doing supports the central portions of the individual sheets as they are transported toward the wrapping machine W.

The master valve

75

Referring to Figs. 7 and 14, a shaft 76, suitably secured to cam 7, is supported in one arm of a bracket 77 carried by side frames 3 and 3a. A mitre gear 78, secured to shaft 76, meshes with a corresponding mitre gear 79 secured to a transverse shaft 80 mounted in bearings in the side frames 3 and 3a and another arm of bracket 77. A cam drum 81, keyed to shaft 80, comprises a plurality of cam surfaces 82 and 82a utilizable to actuate the valve structure, hereinafter described.

The master valve V, Figs. 17-20, comprises a casing 83 suitably attached to bar 67. A cover plate 84, suitably secured to casing 83, as by the screws 85, comprises a stem 86 provided with a plurality of guide passages constituting bearings for the valve cylinders, hereinafter described. Casing 83 comprises a vertical wall 87 providing a suction or vacuum chamber 88 connected by a pipe or conduit 89 to a suitable vacuum pump (not shown), Fig. 18. Wall 87 is provided with a series of guide passages, each in vertical alignment with the guide passages in stem 86 referred to above. Another chamber corresponding with chamber 88 is traversed by two spaced vertical walls 90 and 91 extending substantially at right angles to wall 87, thereby forming three substantially similar chambers 92, 93, and 94. A port 95 opens from suction chamber 88 into one of the passages in wall 87 described above, and a similar port 96 opens from said passage into chamber 92, which is also placed in communication with another passage in wall 87 by a port 97. A port 95a, corresponding to port 95, opens from suction chamber 88 into another of said passages in wall 87, and a port 96a corresponding to port 96 opens from said passage into chamber 93, which is also placed in communication with another passage in wall 87 by a port 97a corresponding to port 97. The third chamber 94 is likewise placed in communication with two other passages in wall 87 by ports 96b and 97b, and a port 95b opens from suction chamber 88 into that passage into which port 96b opens.

Referring to Figs. 17 and 19, a valve cylinder 98a is shown as slidably mounted in that passage of wall 87 communicating with ports 95a and 96a and the passage in stem 86 in alignment therewith. Cylinder 98a comprises a peripheral groove or recess 99a movable into the region of ports 95a and 96a under 125

the influence of a coil spring 100a, or equivalent, partly confined in a recess in said cylinder and engaging a disk 101a, or equivalent, suitably secured to casing 83. Cylinder 98a further comprises a stem 102a protruding through an opening in a cover plate 103 suitably secured to stem 86.

It is to be understood that a similar valve cylinder 98 is slidably mounted in that passage of wall 87 communicating with ports 95 and 96, and the passage in stem 86 in alignment therewith. Further, another valve cylinder 98b, corresponding with cylinders 98 and 98a, is slidably mounted in that passage 15 of wall 87 communicating with ports 95b and 96b, and the passage in stem 86 in alignment therewith.

Referring to Figs. 17 and 18, a valve cylinder 104 is shown as slidably mounted in that 20 passage of wall 87 communicating with port 97 and the passage in stem 86 in alignment therewith. Cylinder 104 is recessed throughout substantially its entire length, and one end thereof communicates directly with the 25 atmosphere. One or more openings 105 in the wall of cylinder 104 may be moved into the region of port 97 by a coil spring 106, or equivalent, partly confined in the recess mentioned above and engaging a disk 107, or 30 equivalent, suitably secured to casing 83. Cylinder 104 further comprises a stem 108 protruding through an opening in cover plate 103.

It is to be understood that a similar valve 35 cylinder 104a is slidably mounted in that passage of wall 87 communicating with port 97a, and the passage in stem 86 in alignment therewith. Further, another valve cylinder 104b, corresponding with cylinders 104 and 104a, is 40 slidably mounted in that passage of wall 87 communicating with port 97b, and the passage in stem 86 in alignment therewith.

Stems 102, 102a and 102b, comprised in the 45 valve cylinders 98, 98a and 98b, extend, respectively, into engagement with levers 109 pivoted, respectively, to brackets 110 carried by cover plate 84. Each lever 109 carries a roller 111 engaging one of the series of cam surfaces 82 on cam drum 81. Stems 108, 108a 50 and 108b comprised in the valve cylinders 104, 104a and 104b extend, respectively, into engagement with levers 112 pivoted, respectively, on said brackets 110. Each lever 112 carries a roller 113 engaging one of the series 55 of cam surfaces 82a on cam drum 81.

As shown in Fig. 18, spring 106 holds valve cylinder 104 in its upward position, thereby opening chamber 92 to the atmosphere until lever 112 is engaged by cam track 82a and 60 swung in a counterclockwise direction, whereupon the series of openings 115 are moved downwardly out of the region of port 97 and chamber 92 is closed from the atmosphere. During the period that chamber 92 is open to 65 the atmosphere, the lever 109 controlling

valve cylinder 98 is engaged by a cam surface 82, and as a result, the circumferential groove in said cylinder is held away from the region of ports 95 and 96. But as chamber 92 is closed, as aforesaid, the cam surface 82 controlling valve cylinder 98 moves from engagement with its co-operating lever 109, and as a result, valve cylinder 98 moves to its upper position under the influence of the spring 100 corresponding with spring 100a. In so doing, chamber 92 is placed in communication with suction chamber 88 through the ports 95 and 96, and the circumferential groove in the valve cylinder. Accordingly, chamber 92 becomes a suction chamber, and so remains until the valve cylinders 98 and 104 are controlled in a manner the reverse of that just described, whereupon said chamber is opened to the atmosphere.

Chambers 93 and 94 are controlled in a 85 manner similar to that described above with respect to chamber 92, although it is to be understood that the groups of cam surfaces 82 and 82a on cam drum 81 are so located that said chambers will be exhausted to the atmosphere or placed in communication with suction chamber 88 at the proper times to effectuate advance of individual sheets toward the wrapping machine, as hereinafter described.

One of the chambers, for example, chamber 92, is connected to a flexible pipe or conduit 114 leading to a fitting common to pipes 43 and 43a connected, respectively, to the chambers in tubes 37 and 37a nearest the adhesive-applying unit. Another chamber, for example, chamber 93, is connected to a flexible pipe or conduit 115 leading to a fitting common to pipes 47 and 47a connected, respectively, to the chambers in tubes 37 and 37a removed from the adhesively-applying unit. Still another chamber, for example, chamber 94, is connected to a flexible pipe or conduit 116 leading to a fitting common to pipes 32 and 32a connected to chambers 31 and 31a, 100 in turn connected to reciprocatory tubes 30 and 30a.

Sheet-stopping mechanism

Referring to Fig. 14, a mitre gear 117 keyed to shaft 80 meshes with and drives a mating mitre gear 118 keyed to a shaft 119 journaled in bearings 120 formed exteriorly of side frame 3a. A mitre gear 121 keyed to shaft 119 meshes with and drives a mating mitre gear 122 keyed to a shaft 123 mounted in bearings in the side frames 3 and 3a. A pair of spiral gears 124 and 124a, splined to shaft 123, are secured, respectively, to sleeves 125 and 125a, rotatably mounted in the conveyer frames 24 and 24a. One time shafts 126 and 126a supported respectively by bearings, not shown, on the conveyer frames 24 and 24a carry, respectively, spiral gears 127 and 127a, 120 125 126 127 128 129 130

meshing with and driven, respectively, by the spiral gears 124 and 124a.

One time shafts 126 and 126a extend longitudinally of the conveyer unit C substantially parallel with the side frames 24 and 24a, and adjacent the adhesive-applying unit G carry, respectively, the cams 128 and 128a, Fig. 9. Once for each cycle of operation of the wrapping machine W, cams 128 and 128a respectively engage rollers 129 and 129a, respectively carried by levers 130 and 130a, mounted on pivots 131 and 131a carried by the respective side frames 24 and 24a. Levers 130 and 130a are held toward cams 128 and 128a by springs 132 and 132a, and when depressed by said cams, rollers 133 and 133a, carried respectively by said levers 130 and 130a, engage levers 134 and 134a, mounted, respectively, on pivots 135 and 135a, carried respectively by the conveyer frames 24 and 24a. A spring 136 holds lever 134 in engagement with roller 133, Fig. 1, and a similar spring, not shown, holds lever 134a in engagement with roller 133a. Levers 134 and 134a, respectively, comprise slots 136 and 136a, receiving shanks 137 and 137a, adjustable therein and held in adjusted position by set screws 138 and 138a, or equivalent devices. Fingers 139 and 139a, preferably formed integrally with shanks 137 and 137a, extend downwardly into the path of the oncoming glued sheet, and are periodically moved from said path in timed relation with the wrapping mechanism, as hereinafter more fully described.

Sheet-transfer mechanism between the adhesive-applying unit and the conveyer unit

Individual glued sheets after passing through the adhesive-applying unit may be transported to the receiving end of the conveyer unit C by any suitable mechanism. Preferably, however, such mechanism is of the character shown in Fig. 1, wherein shaft 140, mounted in bearings in the frame members of the adhesive-applying unit, is the usual member for effecting intermittent step-by-step movement of the usual belt structure of such unit. Shaft 140 is rotated by the power mechanism of the unit G, and, as well understood in the art, is intermittently rotated in timed relation therewith to advance the belt structure of the unit just after a sheet has left the glue roll and been deposited on said belt structure. Shaft 140 carries a gear 141 meshing with an idler gear 142 mounted on a stud 143 mounted in one of the frame members of the adhesive-applying unit. A gear 144 keyed to a shaft 145 mounted in bearings in the auxiliary pivoted frames 145e of the adhesive-applying unit meshes with and is driven by idler gear 142.

Sprockets 146 and 146a, splined to shaft 145, respectively receive and drive the sprocket chains 147 and 147a, belts, or equiv-

alent, said chains passing, respectively, over the sprockets 148 and 148a, Fig. 8, mounted, respectively, on studs or pins 149 and 149a, which in turn are mounted, respectively, in frames 150 and 150a. Arms 151 and 151a, 70 also mounted, respectively, on pins 149 and 149a, extend upwardly, and are mounted on the conveyer frames 24 and 24a on pins 152 and 152a. Frames 150 and 150a extend toward the adhesive-applying unit and are 75 mounted respectively on sleeves, not shown, formed preferably integrally with sprockets 146 and 146a. Chain guides 153 and 153a carried respectively by frames 150 and 150a respectively support the lower spans of 80 chains 147 and 147a.

If the adhesive-applying unit G should become jammed, or if for any other reason it should be desirable to expose the interior mechanism of said unit, frames 145e may be 85 swung on their pivots, not shown, to move shaft 145 and frames 150 and 150a toward the right, Fig. 1. In so doing, chains 147 and 147a sag and arms 151 and 151a swing interiorly of conveyer frames 24 and 24a on 90 their respective pivots 152 and 152a.

As stated hereinbefore, conveyer frames 24 and 24a are adjustable in a lateral sense with respect to the longitudinal axis of the conveyer unit C, and when so adjusted, 95 frames 150 and 150a move therewith, the ends of said last-mentioned frames and the gears 146 and 146a sliding on shaft 145.

Chains 147 and 147a may be equipped with any suitable form of mechanism for gripping individual glued sheets passing from the adhesive-applying unit and transporting the same to the receiving end of the conveyer unit C. Preferably, however, such mechanism takes the form of that disclosed and 100 claimed in our pending application Serial No. 40,769, filed July 1, 1925, and, accordingly, said chains are shown as carrying transversely aligned grippers G1, each preferably taking the place of a chain side link and comprising a plate bracket 154 suitably secured to adjacent chain link pins, one of which forms a bearing for the gripper palm 155, whose palm proper 156 is suitably biased, as by a spring (not shown) into engagement with the circular disk or wheel 157 mounted on a stud carried by plate bracket 154. Gripper palm 155 also comprises an arm 158, 110 utilizable as hereinafter described.

Immediately adjacent the adhesive-applying unit, chain guides 153 and 153a carry bars 159, adjustable longitudinally thereof, each bar comprising a cam surface 160 which co-acts with arm 158 of one of the gripper palms to depress the palm proper 156 and 115 place the gripper in condition to receive the oncoming sheet from the adhesive-applying unit.

In the region occupied by the ends of suction rods 37 and 37a, chain guides 153 and 130

153a carry other bars 161 adjustable longitudinally thereof, each bar comprising a cam surface 162, which also co-acts with arm 158 of one of the gripper units to again depress the palm proper 156, to the end that the glued sheet may be released from the gripper unit.

Suitable bars 163, resting at one end on a grooved rod 164 carried by the frame members of the adhesive-applying unit and at their other end on a rod 165 secured to the conveyer frames 24 and 24a, serve to support the sheet as it is transported from the unit G toward the unit C.

15 *The synchronizing mechanism.*

The unit C, and hence the unit W, may be synchronized with the unit G in any suitable manner. Preferably, however, this synchronizing arrangement takes the form of that illustrated in our co-pending application, Serial No. 40,769, filed July 1, 1925, and as shown in Fig. 2 comprises a cam 170 carried by shaft 80, which rotates once, as the wrapping machine W passes through one cycle of operation and rocks a lever 171 pivoted to the side frame 3a. A hook 172 carried by said lever is fastened to a rod, link or equivalent 173, extending to the tripping mechanism, not shown, of the adhesive-applying unit. It is to be understood that cam 170 is so positioned on shaft 80 that the unit G will be successively actuated at proper times to eventually cause individual sheets to reach the wrapping machine W at the proper time for co-action with the form block structure comprised in said machine.

The operation is as follows:

Initially, a sheet of the desired size is placed in proper position on the lower form of the form block structure w, whereupon the conveyer frames 24 and 24a are adjusted transversely of the machine until suction palms 50 and 50a comprised respectively in the ends of tubes 48 and 48a are in position below the sheet at opposite advanced corners thereof, as shown in Fig. 6. This adjustment is effected by loosening the clamping bolts 21 which passes through the collar 20, Figs. 10 and 13, after which, rotation of shaft 18 shifts racks 28 and 28a either forward or backward, as found necessary, to likewise move the reciprocating suction tubes 30 and 30a. In response to movement of reciprocating suction tubes 30 and 30a tubes 48 and 48a are positioned as indicated above. Bolt 21 is now moved into clamping position. Adjustment of the stationary suction tubes 37 and 37a is next effected by moving the supporting guide members 36 and 36a until the suction heads 53 comprised in said stationary tubes are in transverse alignment with the suction heads 52 comprised in the reciprocating suction tubes.

65 The same sheet or one identical therewith

is now placed in proper position in the transversely aligned gripper units G1 carried by the chains 147 and 147a whereupon movement of the chains is effected in the direction of the arrow, Fig. 1, until the bottom surface of the advanced edge of the sheet is well over the suction holes in the suction heads 53 comprised in the ends of the fixed suction rods 37 and 37a nearest the adhesive applying unit G. Thereafter, fingers 139 and 139a are moved into engagement with the advanced edge of the sheet and the set screws 138 and 138a are clamped into engagement with shanks 137 and 137a which, as stated above, are connected respectively to said fingers. As the final phase of this adjustment, cams 162 comprised in the bars 161 are adjusted by moving said bars in a proper direction until the cams are in such position that the transversely aligned gripper units G1 will be opened to release the sheets in the selected position as they are thereafter fed from the glued unit G.

The units G and W are now placed in operation, the latter functioning to operate the conveyer unit C through the oscillating arm 12. The feed of individual sheets from unit G is effected, however, at a predetermined period in the cycle of operation of the wrapping machine W and conveying unit C by the trip mechanism, described above.

When the unit G is tripped, a sheet is automatically removed from stack a and passed through the various rolls to apply a coating of adhesive to a surface thereof, and passes from the gluing roll c toward a pair of now stationary grippers G1, whose arms 158 have been depressed by cams 160 to move the palms proper 156 from the wheels 157, Fig. 1. The forward edge of the sheet passes into the grippers between said palms and the wheels 157, and immediately thereafter shaft 140 is rotated to actuate gear wheel 141 to effect movement of the lower spans of chains 147 and 147a toward the conveyer unit C. But slight movement is necessary to disengage arms 158 from cams 160, whereupon palms 156 move toward the wheels 157 and grip the forward edge of the sheet. Thereafter, the sheet is transported along the supporting rods 163 toward the conveyer unit C.

Cams 128 and 128a, respectively, are so positioned on shafts 126 and 126a, herein termed "one time" shafts, due to the fact that one, and only one, revolution thereof is effected as the wrapping machine W passes through one cycle of operation, that the high points thereof depress levers 134 and 134a to move fingers 139 and 139a into the path of the advancing sheet prior to the time that arms 158 of the gripper units G1 respectively engage cams 162 to open said units to release the sheet whose forward edge engages fingers 139 and 139a, just as release is effected. The pair of gripper units G1 pass

on without pause until another pair thereof are positioned in sheet-receiving position immediately adjacent the gluing roll *c*. At that time, rotation of shaft 140 automatically ceases, whereupon chains 147 and 147a assume a stationary position and so remain until another sheet has passed through the unit *G* into the pair of grippers last mentioned.

- 10 The sheet, upon release from the pair of grippers, as aforesaid, came to rest in a horizontal position on the ends of stationary suction rods 37 and 37a. Just as release was effected, the master valve *V* became effective to place chamber 92 which is connected to the chambers in tubes 37 and 37a nearest the adhesive-applying unit in communication with suction chamber 88. As a result, the sheet is positively retained in engagement with the 15 suction heads 53 comprised in the ends of said tubes 37 and 37a.

Thereafter, the high points of cams 128 and 128a pass on and fingers 139 and 139a are raised out of the path of the sheet, under 20 the influence of the springs described above.

While the sheet remains in this position, suction rods 30 and 30a under the influence of reciprocating racks 28 and 28a are moved toward the unit *G*. While so moving, however, chamber 94, which is connected to said suction rods, is in communication with the atmosphere through its valve cylinder 104a. However, when suction rods 30 and 30a have been advanced to the full extent toward the 25 unit *G* and while the suction heads 52 comprised in the ends of said rods are lying side-by-side, and in transverse alignment with suction heads 53 comprised in the ends of fixed rods 37 and 37a, the master valve *V* becomes effective to connect chamber 94 to suction chamber 88 and immediately thereafter exhaust chamber 92 to the atmosphere. Thereupon, reverse movement of suction rods 30 and 30a from the unit *G* is instituted, 40 the suction heads 52 comprised in the ends of said rods meanwhile retaining the sheet in engagement therewith and transporting it toward the unit *W*.

When the master valve *V* functioned to 50 connect chamber 94 to suction chamber 88 and to exhaust chamber 92 to the atmosphere, as described above, chamber 93, which is connected to the chambers in fixed suction rods 37 and 37a removed from the unit *G*, 55 was likewise exhausted to the atmosphere. Accordingly, the suction heads 52 comprised in the ends of rods 30 and 30a, in advancing to the full extent toward the unit *W* and assuming a side-by-side position in transverse 60 alignment with the second set of suction heads 53 in fixed rods 37 and 37a, may freely move the sheet directly thereabove.

While said rods 30 and 30a pause momentarily preparatory to again moving toward 65 the unit *G*, the master valve *V* becomes effec-

tive to connect chamber 93 to suction chamber 88 and immediately thereafter exhaust chamber 94 to the atmosphere. As a result, the sheet is released from the movable suction rods 30 and 30a and retained by the second set of suction heads 53 in the fixed rods 37 and 37a; the movable suction rods meanwhile returning toward the unit *G* for the next sheet, which is now in position on the suction heads 53 comprised in the ends of rods 37 and 37a.

In this manner and by successive stages, individual sheets are transported toward the wrapping unit *W*, the suction palms 50 and 50a comprised in the ends of movable suction rods 30 and 30a positioning the individual sheets in the path of the form block structure of said unit just prior to the beginning of a cycle of operation thereof.

As described above, the actuating pulleys for the belts *B*, *B*a and *B*1 are driven only while the movable suction rods are moving toward the unit *W*. As a result, there is provided a support for the sheets, movable, however, only when the sheets move.

Inasmuch as it is desirable to effect a relatively higher velocity of sheet movement by the gripper units *G*1 than is effected by the suction rods, it is necessary to retain the sheet at its first station on the fixed rods 37 and 37a for a longer period than at subsequent stations. To this end, it is necessary to separate each fixed suction rod into two chambers, as described above. Obviously, then, chamber 92 in the master valve controlling the chambers in the suction rods nearest unit *G* must be placed in communication with suction chamber 88 somewhat earlier in each cycle of operation than are the other chambers in said rods. To this end, cam surface 82 on cam drum 81 controlling communication of chambers 88 and 92 may be positioned as desired to effect this result at any desired time. This does not alter the fact that all chambers in the fixed suction rods should be released at the same time, namely, just before suction rods 30 and 30a commence movement toward the unit *W*.

Box structures of any desired character may be periodically fed beneath the form block structure of the wrapping machine by any suitable mechanism and in timed relation with said wrapping machine, each box structure arriving in position substantially coincidentally with the arrival of a sheet delivered by the mechanism hereinbefore described. Preferably, however, such box-structure-delivering mechanism is of the character described in our pending application Serial No. 40,769, filed July 1, 1925, and is indicated generally herein as comprising the box release structure *S*, Fig. 3, the box advancing belt *S*1, Figs. 2 and 3, and a box pusher bar *S*3, Fig. 3.

Although we have illustrated and described

- sheet-conveying mechanism comprising a pair of chains and associated gripping mechanism for transferring sheets from the adhesive-applying unit G to the conveyer unit 5 C in combination with a series of tubes in the last-mentioned unit wherein sheets are pneumatically gripped during travel toward the wrapping unit W, it shall be understood that other types of conveying mechanisms may be 10 utilized in said unit C, for example, of the character illustrated in our prior application Serial No. 40,769, filed July 1, 1925.
- What we claim is:
1. Sheet conveying mechanism comprising 15 sheet gripping mechanism for transporting sheets in succession to one region, and other sheet conveying mechanism timed therewith for effecting sheet delivery from said region to another region comprising structure for pneumatically retaining individual sheets in engagement therewith, one of said conveying mechanisms effecting sheet transportation at a higher velocity than does said other conveying mechanism.
  - 25 2. In combination, sheet conveying mechanism comprising sheet gripping mechanism for transporting sheets coated with wet adhesive in succession to one region, and other sheet conveying mechanism relatively movable with respect thereto in timed relation therewith and comprising pneumatic structure engaging the uncoated faces of individual sheets to retain them in engagement therewith during movement effecting transportation of sheets from said region to another region.
  - 30 3. In combination, sheet conveying mechanism comprising sheet gripping mechanism for transporting sheets in succession to one region, and other sheet conveying mechanism comprising structure for pneumatically retaining individual sheets in engagement therewith effecting transportation of sheets from said region to another region, said conveying mechanism first mentioned effecting sheet transportation at a higher velocity than does said conveying mechanism second mentioned.
  - 35 4. A conveyer unit comprising a pair of conveyer frames, means for conveying sheets in succession from a region at or adjacent one end of said unit toward the other end thereof, means carried by a conveyer frame for transporting sheets from a region removed from said unit to said one end thereof and means to effect intermittent movement of said conveying and transporting means in timed relation to each other.
  - 40 5. A conveyer unit comprising a pair of conveyer frames, means for conveying sheets in succession from a region at or adjacent one end of said unit toward the other end thereof, an endless conveyer carried by a conveyer frame for transporting sheets from a region removed from said unit to said one end there-
  - 45 of, and means to effect alternate, intermittent movement of said conveying means and endless conveyer.
  6. A conveyer unit comprising a pair of conveyer frames, means for conveying sheets in succession from a region at or adjacent one end of said unit toward the other end thereof, a flexible conveyer carried by a conveyer frame for transporting sheets from a region removed from said unit to said one end thereof, and means to effect transfer of the sheets from the conveying means to said flexible conveyer while both are at rest.
  7. A conveyer unit comprising a pair of conveyer frames, means intermittently movable to convey sheets in succession from a region at or adjacent one end of said unit toward the other end thereof, and an intermittently movable conveyer comprising sheet gripping mechanism carried by a conveyer frame for transporting sheets from a region removed from said unit to said one end thereof, and means effecting release of sheets from said gripping mechanism while said conveyers are stationary.
  8. A conveyer unit comprising a pair of conveyer frames, means for conveying sheets in succession from a region at or adjacent one end of said unit toward the other end thereof, one of said conveyer frames being adjustable in a direction at right angles to the path of sheet movement, and means carried by a conveyer frame and adjustable therewith for transporting sheets from a region removed from said unit to said one end thereof.
  9. A conveyer unit comprising a pair of conveyer frames, means for conveying sheets in succession from a region at or adjacent one end of said unit toward the other end thereof, one of said conveyer frames being adjustable in a direction at right angles to the path of sheet movement, and a flexible conveyer carried by a conveyer frame and adjustable therewith for transporting sheets from a region removed from said unit to said one end thereof.
  10. A conveyor unit comprising a pair of conveyer frames, means for conveying sheets in succession from a region at or adjacent one end of said unit toward the other end thereof, one of said conveyer frames being adjustable in a direction at right angles to the path of sheet movement, and an endless conveyer carried by a conveyer frame and adjustable therewith for transporting sheets from a region removed from said unit to said one end thereof.
  11. A conveyer unit comprising a pair of conveyer frames, means for conveying sheets in succession from a region at or adjacent one end of said unit toward the other end thereof, one of said conveyer frames being adjustable in a direction at right angles to the path of sheet movement, and a chain carried by a conveyer frame and adjustable

therewith for transporting sheets from a region removed from said unit to said one end thereof.

12. A conveyer unit comprising a pair of 5 conveyer frames, means for conveying sheets in succession from a region at or adjacent one end of said unit toward the other end thereof, one of said conveyer frames being adjustable in a direction at right angles to the 10 path of sheet movement, and a conveyer comprising sheet gripping mechanism carried by a conveyer frame and adjustable therewith for transporting sheets from a region removed from said unit to said one end thereof.

13. Mechanism for conveying sheets coated with wet adhesive comprising sheet transporting structure movable along a definite path, means for pneumatically retaining 20 an uncoated surface of a sheet in engagement with said structure, means for releasing said sheet in a predetermined region, and means for temporarily retaining the sheet in said predetermined region.

14. Mechanism for conveying sheets coated with wet adhesive comprising sheet transporting structure movable along a definite path, means for pneumatically retaining an 25 uncoated surface of a sheet in engagement with said structure, means for releasing said sheet in a predetermined region, and pneumatic means engaging said uncoated surface to temporarily retain the sheet in said predetermined region.

15. Mechanism for conveying sheets coated with wet adhesive comprising a station, 30 pneumatic means acting upon the uncoated surface of a sheet for retaining the sheet at said station, and pneumatic means engaging the same surface of the sheet for removing the sheet from said station.

16. Mechanism for conveying sheets coated with wet adhesive comprising a station, pneumatic means engaging an uncoated 45 surface of a sheet for delivering the sheet to said station, and means engaging the uncoated surface for retaining the sheet at said station.

17. Mechanism for conveying sheets coated with wet adhesive comprising a station, 50 pneumatic means engaging an uncoated surface of a sheet for delivering the sheet to said station, and pneumatic means engaging the uncoated surface for retaining the sheet at said station.

18. Mechanism for conveying sheets coated with wet adhesive comprising a station, pneumatic means engaging an uncoated surface of a sheet for delivering the sheet to said 60 station, means engaging the uncoated surface for retaining the sheet at said station, and valve structure controlling said means.

19. Sheet conveying mechanism comprising a plurality of stations, pneumatic means 65 for retaining a sheet at one station, pneumatic

means for removing the sheet from said station to another station, pneumatic means for retaining the sheet at said second-mentioned station, and valve structure controlling said means.

20. Sheet conveying mechanism comprising a reciprocatory tube, a stationary tube, a plurality of suction heads comprised in said stationary tube, and means for producing a partial vacuum in said stationary tube during movement of said reciprocatory tube in one direction.

21. Sheet conveying mechanism comprising a reciprocatory tube, a stationary tube, a plurality of suction heads comprised in said stationary tube, means for producing a partial vacuum in said stationary tube during movement of said reciprocatory tube in one direction, and means for opening said stationary tube to the atmosphere as said reciprocatory tube moves in reverse direction.

22. Sheet conveying mechanism, comprising a tube having adjacent chambers, means for producing a partial vacuum in one of said chambers, means for subsequently producing a partial vacuum in another of said chambers, and means for opening said chambers to the atmosphere at substantially the same time.

23. In a conveying unit, a sheet transporting member, mechanism supporting sheets during transportation by said member, means for reciprocating said member, and means for operating said mechanism.

24. In a conveying unit, a sheet transporting member, mechanism supporting sheets during transportation by said member, means for reciprocating said member, and means for operating said mechanism only during movement of said member in one direction.

25. In a conveying unit, a sheet transporting member, belt supporting sheets during transportation by said member, means for reciprocating said member, and means for moving said belt.

26. In a conveying unit, a sheet transporting member, belt supporting sheets during transportation by said member, means for reciprocating said member, and means for moving said belt only during movement of said member in one direction.

27. In a conveying unit, a sheet transporting member, means for reciprocating said member, means for retaining a sheet in engagement with said member during movement thereof in one direction, a belt supporting a sheet in engagement with said member, and means for moving said belt only during movement of said member in one direction.

28. In a conveying unit, a sheet transporting member, means for reciprocating said member, means for pneumatically retaining a sheet in engagement with said member during movement thereof in one direction, a sheet supporting belt, and means for moving said

belt only during movement of said member in one direction.

29. Sheet conveying mechanism comprising a row of spaced stations, a sheet transporting member extending substantially parallel with a line passing through said stations, a plurality of sheet retaining devices carried by said member, each in lateral alignment with a station, means for reciprocating said member to advance each retaining device into lateral alignment with the next adjacent station and then back to original position, means for retaining a sheet by each retaining device during movement of said member in one direction, and means for retaining the sheets at said stations during movement of said member in reverse direction.

30. Sheet conveying mechanism comprising a row of spaced stations, a sheet transporting member extending substantially parallel with a line passing through said stations, a plurality of sheet retaining devices carried by said member, each in lateral alignment with a station, means for reciprocating said member to advance each retaining device into lateral alignment with the next adjacent station and then back to original position, means for pneumatically retaining a sheet by each retaining device during movement of said member in one direction, and means for pneumatically retaining the sheets at said stations during movement of said member in reverse direction.

31. Sheet conveying mechanism comprising a stationary tube, a plurality of spaced suction heads comprised in said tube, each suction head comprising a sheet retaining station, a sheet transporting tube extending substantially parallel with a line passing through said stations, a plurality of suction heads carried by said sheet transporting tube, each in lateral alignment with a station, means for reciprocating said sheet transporting tube to advance each suction head carried thereby into lateral alignment with the next adjacent station and then back to original position, means for pneumatically retaining a sheet by each suction head carried by said sheet transporting tube during movement thereof in one direction, and means for pneumatically retaining the sheets at said stations during movement of said sheet transporting tube in reverse direction.

32. Sheet conveying mechanism comprising a stationary tube, a plurality of spaced suction heads comprising a stationary tube, a plurality of spaced suction heads comprised in said tube, a second suction tube reciprocatory along a line parallel with a line passing through said suction heads, and means for adjusting said stationary tube in a direction parallel with said second-mentioned tube.

33. Sheet conveying mechanism comprising a normally stationary suction member, a

reciprocating suction member, and means simultaneously to adjust said members transversely of the direction of movement of said reciprocating member.

34. Sheet conveying mechanism comprising a normally stationary suction member, a reciprocating suction member, and means to adjust either or both of said members in the direction of movement of said reciprocating member.

35. Sheet conveying mechanism comprising a normally stationary suction member, a reciprocating suction member, means simultaneously to adjust said members transversely of the direction of movement of said reciprocating member, and means to adjust either or both of said members in the direction of movement of said reciprocating member.

36. Mechanism for conveying wrapper sheets into the path of movement of form-block structure operating in timed relation therewith comprising a member movable into and out of the path of movement of said form-block, means adjustable to determine the forward limit of travel of said member, and pneumatic means to retain a wrapper sheet in engagement with said member during forward movement thereof.

37. Mechanism for conveying wrapper sheets into the path of movement of form block structure comprising conveyer frames adjustable toward and away from each other, members carried thereby movable in timed relation to said form-block structure into and out of the path thereof, and suction means to retain a wrapper sheet in engagement with said members during their forward movement.

38. Mechanism for conveying wrapper sheets into the path of movement of form-block structure comprising conveyer frames adjustable toward and away from each other, members carried thereby movable in timed relation to said form-block structure into and out of the path of movement thereof, means adjustable to determine the forward limit of travel of said members, and suction means to retain a wrapper sheet in engagement with said members during their forward movement.

39. Mechanism for conveying wrapper sheets into the path of movement of form-block structure comprising conveyer frames adjustable toward and away from each other, normally stationary suction members carried thereby, suction members carried thereby reciprocable in a path intersecting the path of movement of and in timed relation to said form-block structure, and means to determine the forward limit of travel of said reciprocating members.

THEODORE A. FEDERWITZ.
WALTER T. BAILEY.

CERTIFICATE OF CORRECTION.

Patent No. 1,804,406.

Granted May 12, 1931, to

THEODORE A. FEDERWITZ ET AL.

It is hereby certified that error appears in the printed specification of the above numbered patent requiring correction as follows: Page 1, line 98, for the misspelled word "loking" read looking; page 7, line 48, for "bolts" read bolt; page 11, lines 55 and 56, claim 32, strike out the words and comma "a plurality of spaced suction heads comprising a stationery tube,"; and that the said Letters Patent should be read with these corrections therein that the same may conform to the record of the case in the Patent Office.

Signed and sealed this 7th day of July, A. D. 1931.
